CLAIM

The ornamental design of the child exerciser/rocker, as shown and described.

DESCRIPTION

FIG. 1 is a perspective view of a child exerciser/rocker showing our new design;

FIG. 2 is a top plan view thereof;

FIG. 3 is a right side elevational view thereof, the left side being a mirror image;

FIG. 4 is a front elevational view thereof, the stabilizing legs in a retracted position;

FIG. 5 is a bottom plan view of FIG. 4, and,

FIG. 6 is a rear elevational view of FIG. 4.
